UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

METAL-PUMP.

1,270,483.

Specification of Letters Patent. Patented June 25, 1918.

Application filed December 24, 1913. Serial No. 808,570.

To all whom it may concern:

Be it known that I, HENRY F. BECHMAN, a citizen of the United States, residing at Battle Creek, in the county of Calhoun and 5 State of Michigan, have invented certain new and useful Improvements in Metal-Pumps; and I hereby declare that the following is a full, clear, and exact description thereof, reference being had to the accompanying drawings, which form part of this 10 specification.

This invention relates to metal pumps particularly such as are used by type founders and stereotypers for pumping molten 15 type metal, and its object is to provide a pump which can be operated with much less manual labor than is required by the present known pumps; and the invention consists in the novel construction and combination of 20 parts hereinafter claimed and described in detail with reference to the accompanying drawings in which—

Figure 1 is a top plan view of the pump in position within a melting pot.

25 Fig. 2 is a sectional view of a melting pot showing the pump in elevation.

Fig. 3 is a detail.

The melting pot A, which may be of ordinary construction and mounted on top of a 30 furnace B in the usual manner, is adapted to contain a large quantity of molten type metal.

Within the pot A is arranged a pump cylinder 1 that is preferably open at its lower 35 end but closed at top except for a small outlet opening which is connected with a discharge pipe 1^a by which the molten metal can be directed out of the chamber into a stereotype casting box, or other suitable receptacle. This pump cylinder 1 may be 40 rigidly connected to and suspended from a bracket 1^b which has an arm 1^c fastened to the top of the pot by bolts 1^d or any other suitable means.

45 The pump piston 3 is adapted to fit easily within the pump cylinder and is rigidly connected to a piston rod 3^a that extends through a suitable opening in the upper end of the pump cylinder, and its upper end 50 is guided in a sleeve 4^b attached to a bracket casting 4, which is shown as secured to the bracket 1^b by means of bolts 4^a. In the normal position of the parts the pump piston 3 lies below and outside of the pump cylinder

and the latter is filled with metal from below, so that dross and slag are excluded from the cylinder.

The bracket 4 is provided with horizontal bearings 4^c for a shaft 5, which shaft has on its inner end a gear 5^a, adapted to mesh with a rack 3^b on the upper end of the piston rod 3^a, which rack may be formed by cutting teeth in the side of the rod as indicated in Fig. 3. The sleeve 4^b preferably has an opening 4^c in its side to permit direct engagement of the gear 5^a with the rack 3^b, while the sleeve 4^b and bearing 4^c are practically integral and close together. On the outer end of the shaft 5 is a crank 6 by which the shaft 5 may be turned by hand.

When the shaft 5 is turned in one direction the piston 3 will be lifted and enter the cylinder 1 and force the molten metal therein out through the pipe 1^a. Any desired amount of metal can be discharged up 75 to the full capacity of the pump cylinder.

Owing to the small diameter of the gear 5^a as compared with the length of the crank 6 great leverage will be exerted to lift the piston 3^a by a slight application of power to 80 the handle 6^a. In the example shown the ratio is about sixteen to one while on ordinary stereotyping pumps operated by levers the ratio is usually six-and-a-half to one, therefore less than half the manual effort 85 is required to pump metal with my invention than is required with the ordinary lever operated apparatus; and further by my pump the metal can be discharged quietly and uniformly instead of violently and suddenly.

The advantages of this invention will be at once appreciated by stereotypers and type founders familiar with the present known types of metal pumps.

What I claim is:

In a molten metal pumping apparatus, the combination of a melting pot; a bracket attached to the top and one side of the pot and depending thereinto; a pump cylinder 100 attached to and suspended from the inner end of said bracket within the pot; a piston in the cylinder; a rod connected with the piston and provided with gear teeth cut therein; a second bracket mounted upon the 105 first bracket adjacent the pump and provided with inner and outer bearings for a horizontal shaft and with a vertical sleeve.

adjacent the inner bearing for guiding the toothed portion of the piston rod, said sleeve also having an opening in its side adjacent the inner bearing; a manually operable shaft 5 mounted in said bearings; a pinion on the inner end of said shaft lying partly within the opening in said sleeve and engaging the teeth of the piston rod through said opening; and a discharge spout connected with

said pump cylinder, substantially as de- 10 scribed.

In testimony that I claim the foregoing as my own, I affix my signature in presence of two witnesses.

HENRY F. BECHMAN.
